(57) **CLAIM**

The ornamental design for a fabric window covering, as shown and described.

DESCRIPTION

FIG. 1 is a front and top perspective view of the fabric window covering shown in an open position;

FIG. 2 is a back and bottom perspective view of thereof;

FIG. 3 is a front view of the design of FIG. 1;

FIG. 4 is a back view thereof;

FIG. 5 is a right side view thereof. The left side view is a mirror image of the right side;

FIG. 6 is a top view thereof;

FIG. 7 is a bottom view thereof;

FIG. 8 is a front and top perspective view of the fabric window covering of FIG. 1 shown in a closed position;

FIG. 9 is a back and bottom perspective view thereof;

FIG. 10 is a front view of FIG. 8;

FIG. 11 is a back view thereof;

FIG. 12 is a right side view thereof. The left side view is a mirror image of the right side;

FIG. 13 is a top view thereof;

FIG. 14 is a bottom view thereof; and,

FIG. 15 is an enlarged view of an exemplary part taken from the bottom right of the front vertical fabric shown in FIG. 1. The dark background is provided for contrast only for purpose of illustration and forms no part of the claimed design.

1 Claim, 15 Drawing Sheets
